Fig. 1.

Fig. 2.

Eig.

This technical cross-sectional diagram illustrates a complex mechanical assembly, possibly a pump or valve mechanism. The diagram is labeled with numerous numbers, likely referring to specific parts or components. Key labeled parts include:

- 10, 10a, 10b, 12b, 36, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, 6624, 6625, 6626, 6627, 6628, 6629, 66210, 66211, 66212, 66213, 66214, 66215, 66216, 66217, 66218, 66219, 66220, 66221, 66222, 66223, 66224, 66225, 66226, 66227, 66228, 66229, 662210, 662211, 662212, 662213, 662214, 662215, 662216, 662217, 662218, 662219, 662220, 662221, 662222, 662223, 662224, 662225, 662226, 662227, 662228, 662229, 6622210, 6622211, 6622212, 6622213, 6622214, 6622215, 6622216, 6622217, 6622218, 6622219, 6622220, 6622221, 6622222, 6622223, 6622224, 6622225, 6622226, 6622227, 6622228, 6622229, 66222210, 66222211, 66222212, 66222213, 66222214, 66222215, 66222216, 66222217, 66222218, 66222219, 66222220, 66222221, 66222222, 66222223, 66222224, 66222225, 66222226, 66222227, 66222228, 66222229, 662222210, 662222211, 662222212, 662222213, 662222214, 662222215, 662222216, 662222217, 662222218, 662222219, 662222220, 662222221, 662222222, 662222223, 662222224, 662222225, 662222226, 662222227, 662222228, 662222229, 6622222210, 6622222211, 6622222212, STATOR STRUCTURE FOR SYNCHRONOUS ELECTRIC MOTORS

Arthur B. Poole, Bristol, Conn., assignor to The E. Ingraham Company, Bristol, Conn., a corporation of Connecticut

Application May 13, 1938, Serial No. 207,670

16 Claims. (Cl. 172—278)

This invention relates to an improvement in stator-structures for synchronous electric-motors, and is primarily concerned with stator-structures for synchronous electric-motors of the type used in propelling clocks and other time-instruments.

One of the objects of the present invention is to provide a superior stator-structure for synchronous electric-motors having a superior concentration of magnetic flux immediately adjacent the rotor of such a motor.

A further object is to provide a superior stator-structure for synchronous electric-motors wherein undue axial draft upon the rotor thereof may be obviated.

Still another object of the present invention is to provide a superior stator-structure whereby magnetic flux may be concentrated immediately adjacent a rotor to thus increase the efficiency of the synchronous motor-structure and at the same time avoid undue axial stresses upon such rotor.

A still further object of the present invention is to provide a superior stator-structure for synchronous electric-motors which will efficiently act upon the rotor without imparting objectionable axial vibration thereto when the stator-structure is energized by alternating or other sinusous current.

With the above and other objects in view, as will appear to those skilled in the art from the present disclosure, this invention includes all features in the said disclosure which are novel over the prior art and which are not claimed in any separate application.

35 In the accompanying drawings, in which certain modes of carrying out the present invention are shown for illustrative purposes:

Fig. 1 is a front elevational view of a synchronous electric motor embodying the stator-structure of the present invention;

Fig. 2 is a view thereof in side elevation;

Fig. 3 is a view showing the casing, the energizing-coil and the major portion of the cup-shaped pole-unit in section on the line 3—3 of Fig. 1;

Fig. 4 is a central sectional view taken on the line 4—4 of Fig. 1;

Fig. 5 is a sectional view taken on the line 5—5 of Fig. 3;

50 Fig. 6 is a perspective view partly in section of the cup-shaped pole-unit together with its shading-disk and annular series of salient poles;

Fig. 7 is a perspective view of the disk-like pole-unit together with its shading-disk and annular series of salient poles; and

Fig. 8 is a perspective view of one of the bar-like salient poles detached.

The stator-structure herein chosen for the purpose of illustrating the present invention includes a cup-shaped pole-unit generally designated by the reference character 10 and a complementary disk-like pole-unit generally designated by the reference character 11, both of which are composed of suitable magnetic material such, for instance, as silicon steel, soft iron or the like. The cup-shaped pole-unit 10 has an end wall 10^a and an annular flange 10^b. The pole-unit just referred to is of duplex character and includes a relatively-deep outer cup-shaped member 12 and a relatively-shallow inner cup-shaped member 13. The outer member 12 just referred to includes an end-wall 12^a and an annular flange 12^b. The inner cup-shaped member 13 is tightly fitted within the outer cup-shaped member 12 and, like the same, includes an end-wall 13^a and an annular flange 13^b, which latter, however, is slightly less in depth than the adjacent flange 12^b of the outer cup-shaped member 12, so that its rear edge 13^c provides a seat for the purpose as will hereinafter appear.

The disk-like pole-unit 11 comprises an outer disk 15 and an inner disk 16 corresponding to each other in size and configuration and jointly fitting within the open end of the outer cup-shaped member 12 of the cup-shaped pole-unit 10 so that the inner disk 16 bears against the outer edge 13^c of the inner cup-shaped member 13 of the aforesaid cup-shaped pole-unit 10. For the purpose of retaining the disk-like pole-unit 11 in place within the cup-shaped member 12 the flange 12^b of the latter may be indented to provide a suitable number of retaining-nibs such, for instance, as the retaining-nib 17 shown in Figs. 3 and 4 of the accompanying drawings.

Projecting rearwardly from the end-wall 10^a of the cup-shaped pole-unit 10 in parallelism with the annular flange 10^b thereof, is an annularly-arranged series of bar-like salient poles 18 (six more or less) formed of soft iron or other suitable magnetic material and arranged in (three more or less) pairs around the axis of the structure formed by the complementary pole-units 10 and 11, so that the individual salient poles of each pair thereof are more closely spaced together than are the several pairs with respect to each adjacent pair. In a similar manner, an annular series of bar-like salient poles, each generally designated by the reference character 19, extend forwardly from the disk-like pole-unit 11. The salient poles 19 are arranged in a manner

corresponding to that described in connection with the salient poles 18 of the disk-like pole-unit 10, so that a pair of salient poles of one of the pole-units fits into a relatively-wide gap between the respective pairs of salient poles of the other unit. The result of the spacing of the salient poles just above described is such that when the two pole-units 10 and 11 are assembled, the salient poles of like polarity are spaced relatively widely apart, while the salient poles of unlike polarity are spaced in very close proximity to each other, as will be apparent by reference to Fig. 5 in particular.

For the purpose of economy in manufacture, 15 the salient poles 18 and 19 above referred to, all correspond to each other in size and form so as to be interchangeable one for the other.

Each of the salient poles 18 and 19 includes a body-portion 20 of substantially rectangular form 20 in cross-section though having a slightly-concaved inner face 21 and a slightly-convexed outer face 22, each of such curvature as to extend substantially concentrically with respect to the axis of the pole-units 10 and 11. Each of the salient 25 poles 18 and 19 is formed at one end with a cylindrical shank 23 which extends with a drive-fit into a suitable perforation 24, an appropriately-spaced annular series of which is formed in the end-wall 10^a of the cup-shaped pole-unit 10 30 and in the disk-like pole-unit 11. Preferably and as shown in Figs. 3 and 4, the ends of the shanks 23 of each salient pole 18 and 19 are headed over as at 25 against the outer face of the immediately-adjacent portion of the particular pole-unit 10 35 or 11 in which the particular salient pole is mounted as described.

At the extreme end of each salient pole 18 and 19 opposite its shank 23, there is provided a stabilizing-tenon 26 for the purpose as will hereinafter appear. Each salient pole 18 and 19 is formed intermediate its rectangular body-portion 20 and its stabilizing-tenon 26 with a cylindrically-contoured flux-restricting neck or portion 27 which as will more fully hereinafter appear, 45 serves to restrict the flow of magnetic flux and cause the latter to flow mainly from the body-portion 20 to a rotor-unit.

As thus constructed and arranged the stator-structure includes two spaced-apart magnetic-portions (the end wall 10^a and the pole-unit 11) from each of which salient poles project toward the other magnetic-portion.

Positioned against the inner face of the end-wall 10^a of the cup-shaped pole-unit 10 is a shading-disk 28 composed of copper or other suitable high-electro-conductive material and formed with an annular series of substantially-rectangular perforations 29, each of which is shaped and located so as to snugly fit over the base of the body-portion 20 of one of the salient poles 18 of the pole-unit 10, to thus supplement the action of the shank 23 of a given salient pole in holding the same in properly-oriented position. Each alternate one of the polygonal perforations 29 is intersected by a radial slot 30 which thus interrupts the flow of induced current in the portion of the shading-disk 28 around the particular one of the salient poles 18 which happens to extend through one of the said intersected perforations 29. The remaining three perforations 29 are not intersected by slots, as will be seen by reference to Fig. 6, and the material of the shading-disk 28 which surrounds them is electrically continuous and provides a complete electrical path for 70 the flow of induced current around the particular 75

three salient poles 18 projecting through the said non-intersected perforations 29.

From the foregoing it will be seen that each alternate one of the salient poles 18 is shaded, so to speak, by the shading-disk 28 so that the magnetic flux in these particular salient poles will lag with respect to the magnetic flux in the remaining three unshaded salient poles 18 so as to produce a rotating-field effect.

Positioned against the inner face of the disk-like pole-unit 11 is a shading-disk 31 corresponding in its main characteristics and functions to the shading-disk 28 just above described and like the same, provided with six (more or less) substantially-rectangular perforations 32, each of 15 which snugly fits over the base of the substantially-rectangular body-portion 20 of one of the salient poles 19 of the disk-like pole-unit 11. The material of the shading-disk 31 (copper or the like) around three of the six perforations 32 is 20 electrically continuous so as to provide for the flow of induced currents around the particular three salient poles 19 respectively extending therethrough. The remaining three perforations 32 in the shading-disk 31 are, as is particularly 25 well shown in Fig. 7, intersected by radial slots 33 extending through the outer edge of the disk 31 and serving to interrupt the flow of induced current around the particular three salient poles 19 extending through these latter three intersected 30 perforations 32.

From the foregoing it will be seen that three of the salient poles 19 of the disk-like pole-unit 11 are shaded by the shading-disk 31 so that the magnetic flux flowing therethrough will lag with 35 respect to the magnetic flux flowing through the remaining three salient poles 19 which extend through the particular perforations 32 which are intersected by the radial slots 33 above described. This shading of alternate salient poles 19 produces a rotating-field effect similar to that described in connection with the salient poles 18 of the pole-unit 10 and having a similar direction of rotation so as to exert a turning torque upon a 40 rotor-unit to be later described.

The stabilizing-tenon 26 at the otherwise free end of each of the salient poles 18 is preferably slightly tapered for being forced with a drive-fit into a correspondingly-located perforation 34 (one of six perforations) in the shading-disk 31 50 of the disk-like pole-unit 11. Thus, each of the respective opposite ends of each of the bar-like salient poles 18 is firmly held against displacement or vibration under the influence of pulsating magnetic flux.

In a similar manner, the stabilizing-tenons 26 of the salient poles 19 of the disk-like pole-unit 11 are each preferably slightly tapered for being forced with a drive-fit into an aligned perforation (one of six perforations) 35 in the shading-disk 28 of the cup-shaped pole-unit 10, so that the otherwise free ends of the said salient poles 19 are also firmly held against displacement or vibration.

Surrounding the salient poles 18 and 19 which as before explained, are arranged in an annular series, is an energizing-coil 36 having two insulated leads 37 and 38 which project through one of the three radial slots 33 in the adjacent shading-disk 31 and thence through passages 39 and 40 formed in the disk-like pole-unit 11.

Enclosed within the central annular space outlined by the series of salient poles 18 and 19 before described, is a rotor-unit which for convenience of description will be generally design- 75

nated by the reference character 41. The said rotor-unit is of composite character and includes a rotor-hub 42 which is preferably formed of non-magnetic material such, for instance, as brass, and upon which is rigidly mounted a pair of corresponding but oppositely-facing cup-shaped rotor-elements 43-43. The said rotor-elements 43-43 are preferably formed of hard steel or other suitable permanent-magnet material and are spaced from each other by a salient-poled rotor-element 44 which is preferably formed of soft iron or other non-permanent magnetic material. The said cup-shaped rotor-elements 43-43 preferably have smooth outer peripheries 10 so as not to provide marked geometrically-salient poles but which, owing to their permanent magnetic character are adapted to receive magnetic "spottings" so to speak, which will be impressed upon them by the adjacent salient poles of the 20 stator-structure, in accordance with well-understood principles in the art.

The rotor-hub 42 is provided at its forward end with a sleeve-like bearing-portion 45 which rotates upon the adjacent surface of a center-arbor 25 46 which in turn is journaled at its forward end in a bearing-opening 47 in the adjacent shading-disk 28. The rear portion of the center-arbor 46 bears in a bearing-opening 48 formed in a bearing-plate 49 which latter is located in spaced 30 relationship rearwardly of the disk-like pole-unit 11 before referred to. The said bearing-plate 49 is supported in spaced relationship as just described by means of a suitable number of pillars 50 as is indicated in Figs. 3 and 4.

35 The rear end of the rotor-hub 42 is formed with a rearwardly-extending sleeve-like portion 51 having an axial passage 52 extending therethrough as well as through the main portion of the adjacent rotor-hub 42 proper as is shown in Fig. 4. The axial passage 52 just referred to is considerably larger in diameter than the diameter of the center-arbor 46 which extends therethrough, and receives at its rear end with a drive-fit the forward end of a drive-pinion 53 which 40 bears with freedom for rotation upon the center-arbor 46 and permits oil to enter the interior 45 of the rotor-hub by way of the gaps between its gear-teeth.

As thus constructed and arranged, the rotor-unit rigidly carries the drive-pinion 53 and the latter acts through a reduction-gear-train generally designated by the reference character 54 to drive a power-output shaft 55 from which may be driven a clock-mechanism or the like. The particular character of the reduction-gear-train 54 is not here involved and it need not be described in detail other than to say, as above, that it serves to operatively interconnect the drive-pinion 53 of the rotor-unit 41 with the power-output 50 shaft 55.

In the structure shown, all of the parts above described, with the exception of the forward end of the power-output shaft 55, are housed within a two-part housing generally designated by the reference character 56, and which may if desired be made of relatively-light sheet-steel or other suitable material of an oil-tight nature. The said housing 56 includes a relatively-deep cup-shaped housing-member generally designated by the reference character 57 and which has a substantially-flat rear end-wall 58 and a deep annular flange 59. The open forward end of the cup-shaped housing-member 57 is closed by a flanged housing-cap generally designated by the reference character 60 and which includes a sub-

stantially-flat end-wall 61 and a relatively-shallow rearwardly-projecting annular flange 62 which fits over the exterior of the adjacent open end of the flange 59 of the main housing-member 57 and is preferably cemented, soldered or otherwise sealed in an oil-tight manner to the said housing-member 57.

The leads 37 and 38 of the energizing-coil 36 may be led outwardly from the interior to the exterior of the housing 56 in any suitable manner, such, for instance, as through terminal-fittings 63 and 64 and may be exteriorly connected to supply-wires 65 and 66, as indicated in Figs. 1 and 2 in particular.

As before noted, the present invention is concerned mainly with the stator-structure which comprises in the main, the cup-shaped pole-unit 10, the disk-like pole-unit 11, the salient poles 18 and 19 projecting therefrom.

By providing each of the salient poles 18 and 19 with a reduced portion or neck, such as 27, the magnetic flux flowing from a given one of the said salient poles to the rotor is restricted at this point and compelled to mainly flow directly to the rotor-unit 41 from the relatively-large body-portions 20 of the said salient poles. It will be noted that the body-portions 20 have inner faces of much greater width or extent in the direction of rotation of the rotor-unit 41 than have the said flux-restricting necks 27.

Furthermore, by locating the flux-restricting necks 27 at the outer end of each salient pole, rather than at the inner end thereof, the desired effect is achieved without materially affecting the flow of magnetic flux into a given salient pole 35 from the particular pole-unit of which it forms a feature.

As will be seen most clearly by reference to Figs. 3 and 4 of the accompanying drawings, the provision of the salient poles 18 and 19 with the flux-restricting necks 27 or their equivalent, the magnetic flux is concentrated mainly upon the periphery of the rotor-unit 41 without exerting such degree of axial draft upon the same as would cause the rotor-unit to materially shift or vibrate 45 axially to thereby possibly cause the faulty operation of the motor and produce objectionable hum due to the constantly-changing polarities of the respective pole-units 10 and 11 and their 50 respective salient poles 18 and 19.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A stator-structure for cooperation with the rotor of a synchronous electric motor, including in combination: a first magnetic-portion; a second magnetic-portion spaced from the said first magnetic-portion and extending in substantial parallelism therewith; a plurality of salient poles projecting laterally from the said first magnetic-portion toward the said second magnetic-portion; a plurality of salient poles projecting laterally in the opposite direction from the said second magnetic-portion toward the said first magnetic-portion; and an energizing-coil for magnetizing the two said magnetic-ports and the oppositely-projecting salient poles; each of the said salient poles of each of the said magnetic-

- portions comprising a portion of relatively-large cross-sectional area and a portion of materially-lesser cross-sectional area; the portions of the said materially-lesser cross-sectional area being arranged in the oppositely-projecting salient poles for positioning remotely with respect to the rotor, and the portions of the said relatively-large cross-sectional area being located in the said salient poles for positioning in corresponding proximate relation to the rotor, whereby the latter portions of the salient poles provide in the magnetic-field of the stator-structure, a zone of relatively-high magnetic flux arranged to be traversed by the rotor.
2. A stator-structure for cooperation with the rotor of a synchronous electric motor, including in combination: a first magnetic-portion; a second magnetic-portion spaced from the said first magnetic-portion and extending in substantial parallelism therewith; a plurality of salient poles projecting laterally from the said first magnetic-portion toward the said second magnetic-portion; a plurality of salient poles projecting laterally in the opposite direction from the said second magnetic-portion toward the said first magnetic-portion; and an energizing-coil for magnetizing the two said magnetic-portions and the oppositely projecting salient poles; each of the said salient poles of each of the said magnetic-portions comprising a portion of relatively-large cross-sectional area and a portion of materially-lesser cross-sectional area located at the outer end of its projecting end; the portions of the said materially-lesser cross-sectional area being arranged in the oppositely-projecting salient poles for positioning remotely with respect to the rotor, and the portions of the said relatively-large cross-sectional area being located in the said salient poles for positioning in corresponding proximate relation to the rotor, whereby the latter portions of the salient poles provide in the magnetic-field of the stator-structure, a zone of relatively-high magnetic flux arranged to be traversed by the rotor.
3. A stator-structure for cooperation with the rotor of a synchronous electric motor, including in combination: a first magnetic-portion; a second magnetic-portion spaced from the said first magnetic-portion and extending in substantial parallelism therewith; a plurality of salient poles projecting laterally from the said first magnetic-portion toward the said second magnetic-portion; a plurality of salient poles projecting laterally in the opposite direction from the said second magnetic-portion toward the said first magnetic-portion; and an energizing-coil for magnetizing the two said magnetic-portions and the oppositely-projecting salient poles; each of the said salient poles of each of the said magnetic-portions comprising a portion having an inner facial width of relatively-great extent and each of the said salient poles also having a portion of materially-lesser inner facial extent; the portions of the said materially-lesser inner facial width being arranged in the oppositely-projecting salient poles for positioning remotely with respect to the rotor, and the portions of the said relatively-great inner facial width being located in the said salient poles for positioning in corresponding proximate relation to the rotor, whereby the latter portions of the salient poles provide in the magnetic-field of the stator-structure, a zone of relatively-high magnetic flux arranged to be traversed by the rotor.
4. A stator-structure for cooperation with the rotor of a synchronous electric motor, including in combination: a first magnetic-portion; a second magnetic-portion spaced from the said first magnetic-portion and extending in substantial parallelism therewith; a plurality of salient poles projecting laterally from the said first magnetic-portion toward the said second magnetic-portion; a plurality of salient poles projecting laterally in the opposite direction from the said second magnetic-portion toward the said first magnetic-portion; and an energizing-coil for magnetizing the two said magnetic-portions and the oppositely-projecting salient poles; each of the said salient poles of each of the said magnetic-portions comprising a portion having an inner facial width of relatively-great extent and each of the said salient poles also having a portion of materially-lesser inner facial extent; the portions of the said materially-lesser inner facial width being arranged in the oppositely-projecting salient poles for positioning remotely with respect to the rotor, and the portions of the said relatively-great inner facial width being located in the said salient poles for positioning in corresponding proximate relation to the rotor, whereby the latter portions of the salient poles provide in the magnetic-field of the stator-structure, a zone of relatively-high magnetic flux arranged to be traversed by the rotor.
5. A stator-structure for synchronous electric motors, including in combination: a first magnetic-portion; a second magnetic-portion spaced from the said first magnetic-portion and extending in substantial parallelism therewith; a plurality of salient poles projecting from the said first magnetic-portion toward the said second magnetic-portion; a plurality of salient poles projecting from the said second magnetic-portion toward the said first magnetic-portion; and an energizing-coil for magnetizing the two said magnetic-portions and the salient poles projecting therefrom; each of the said salient poles of each of the said magnetic-portions being provided with a body-portion of substantially-rectangular form in cross-section and a flux-restricting portion of substantially-circular form in cross-section and of materially-lesser cross-sectional area than the said body-portion.
6. A stator-structure for synchronous electric motors, including in combination: a first magnetic-portion; a second magnetic-portion spaced from the said first magnetic-portion and extending in substantial parallelism therewith; a plurality of salient poles projecting from the said first magnetic-portion toward the said second magnetic-portion; a plurality of salient poles projecting from the said second magnetic-portion toward the said first magnetic-portion; and an energizing-coil for magnetizing the two said magnetic-portions and the salient poles projecting therefrom; each of the said salient poles of each of the said magnetic-portions being provided with a body-portion of substantially-rectangular form in cross-section and a flux-restricting portion of substantially-circular form in cross-section and of materially-lesser cross-sectional area than the said body-portion and located at a point beyond the said body-portion remote from the magnetic-portion from which the salient pole projects.
7. A stator-structure for synchronous electric motors, including in combination: a first magnetic-portion; a second magnetic-portion spaced from the said first magnetic-portion and extending in substantial parallelism therewith; a plurality of salient poles projecting from the said first magnetic-portion toward the said second magnetic-portion; a plurality of salient poles projecting from the said second magnetic-portion toward the said first magnetic-portion; and an energizing-coil for magnetizing the two said magnetic-portions and the salient poles projecting therefrom; each of the said salient poles of each of the said magnetic-portions being provided with a body-portion of substantially-rectangular form in cross-section and a flux-restricting portion of substantially-circular form in cross-section and of materially-lesser cross-sectional area than the said body-portion and located at a point beyond the said body-portion remote from the magnetic-portion from which the salient pole projects.

- rality of salient poles projecting from the said first magnetic-portion toward the said second magnetic-portion; a plurality of salient poles projecting from the said second magnetic-portion 5 toward the said first magnetic-portion; and an energizing-coil for magnetizing the two said magnetic-portions and the salient poles projecting therefrom; each of the said salient poles of each of the said magnetic-portions being provided with a body-portion having a concaved inner face of relatively-great width and each of the said salient poles also having a flux-restricting portion having a convex inner face.
8. A stator-structure for synchronous electric-motors, including in combination: a first magnetic-portion; a second magnetic-portion spaced from the said first magnetic-portion and extending in substantial parallelism therewith; a plurality of salient poles projecting from the said 10 first magnetic-portion toward the said second magnetic-portion; a plurality of salient poles projecting from the said second magnetic-portion toward the said first magnetic-portion; and an energizing-coil for magnetizing the two said magnetic-portions and the salient poles projecting therefrom; each of the said salient poles of each of the said magnetic-portions being provided with a body-portion having a concave inner face of relatively-great width and each of the said 15 salient poles also having a flux-restricting portion having a convex inner face which is located at a point on the salient pole on the side of the said body-portion remote from the magnetic-portion by which the salient pole is carried.
9. A stator-structure for cooperation with the rotor of a synchronous electric-motor, including in combination: a cup-shaped pole-unit having an end-wall and a flange; a disk-like pole-unit substantially closing the open end of the said cup-shaped pole-unit; a plurality of salient poles projecting laterally from the end-wall of the said cup-shaped pole unit toward the said disk-like pole-unit; a plurality of salient poles projecting laterally in the opposite direction from the said disk-like pole-unit toward the end-wall of the said cup-shaped pole-unit; and a ring-like energizing-coil located within the said cup-shaped pole-unit intermediate the flange thereof and the oppositely-projecting salient poles; each of the 20 said salient poles of each of the said pole-units comprising a portion of relatively-large cross-sectional area and a portion of materially-lesser cross-sectional area; the portions of the said materially-lesser cross-sectional area being arranged 25 in the oppositely-projecting salient poles for positioning remotely with respect to the rotor, and the portions of the said relatively-large cross-sectional area being located in the said salient poles for positioning in corresponding proximate relation to the rotor, whereby the latter portions of the salient poles provide in the magnetic-field of the stator-structure, a zone of relatively-high magnetic flux arranged to be traversed by the 30 rotor.
10. A stator-structure for cooperation with the rotor of a synchronous electric-motor, including in combination: a cup-shaped pole-unit having an end-wall and a flange; a disk-like pole-unit substantially closing the open end of the said cup-shaped pole-unit; a plurality of salient poles projecting laterally from the end-wall of the said cup-shaped pole-unit toward the said disk-like pole-unit; a plurality of salient poles projecting laterally in the opposite direction from the said disk-like pole-unit toward the end-wall of the 35

said cup-shaped pole-unit; and a ring-like energizing-coil located within the said cup-shaped pole-unit intermediate the flange thereof and the oppositely-projecting salient poles; each of the said salient poles of each of the said pole-units comprising a portion of relatively-large cross-sectional area and a portion of materially-lesser cross-sectional area located at its projecting end; the portions of the said materially-lesser cross-sectional area being arranged in the oppositely-projecting salient poles for positioning remotely with respect to the rotor, and the portions of the said relatively-large cross-sectional area being located in the said salient poles for positioning in corresponding proximate relation to the rotor, whereby the latter portions of the salient poles provide in the magnetic-field of the stator-structure, a zone of relatively-high magnetic flux arranged to be traversed by the rotor.

11. A stator-structure for cooperation with the rotor of a synchronous electric-motor, including in combination: a cup-shaped pole-unit having an end-wall and a flange; a disk-like pole-unit substantially closing the open end of the said cup-shaped pole-unit; a plurality of salient poles projecting laterally from the end-wall of the said cup-shaped pole-unit toward the said disk-like pole-unit; a plurality of salient poles projecting laterally in the opposite direction from the said disk-like pole-unit toward the end-wall of the said cup-shaped pole-unit; and a ring-like energizing-coil located within the said cup-shaped pole-unit intermediate the flange thereof and the oppositely-projecting salient poles; each of the said salient poles of each of the said pole-units comprising a portion having an inner facial width of relatively-great extent and each of the said salient poles also having a portion of materially-lesser inner facial extent; the portions of the said materially-lesser inner facial width being arranged in the oppositely-projecting salient poles for positioning remotely with respect to the rotor, and the portions of the said relatively-great inner facial width being located in the said salient poles for positioning in corresponding proximate relation to the rotor, whereby the latter portions of the salient poles provide in the magnetic-field of the stator-structure, a zone of relatively-high magnetic flux arranged to be traversed by the 40 rotor.

12. A stator-structure for cooperation with the rotor of a synchronous electric-motor, including in combination: a cup-shaped pole-unit having an end-wall and a flange; a disk-like pole-unit substantially closing the open end of the said cup-shaped pole-unit; a plurality of salient poles projecting laterally from the end-wall of the said cup-shaped pole-unit toward the said disk-like pole-unit; a plurality of salient poles projecting laterally in the opposite direction from the said disk-like pole-unit toward the end-wall of the said cup-shaped pole-unit; and a ring-like energizing-coil located within the said cup-shaped pole-unit intermediate the flange thereof and the oppositely-projecting salient poles; each of the said salient poles of each of the said pole-units comprising a portion having an inner facial width of relatively-great extent and each of the said salient poles also having a portion of materially-lesser inner facial extent than the facial extent of the said body-portion located at its projecting end; the portions of the said materially-lesser inner facial width being arranged in the oppositely-projecting salient poles for positioning remotely with respect to the rotor,

and the portions of the said relatively-great inner facial width being located in the said salient poles for positioning in corresponding proximate relation to the rotor, whereby the latter portions 5 of the salient poles provide in the magnetic-field of the stator-structure, a zone of relatively-high magnetic flux arranged to be traversed by the rotor.

13. A stator-structure for synchronous electric-motors, including in combination: a cup-shaped pole-unit having an end-wall and a flange; a disk-like magnetic-portion substantially closing the open end of the said cup-shaped pole-unit; a plurality of salient poles projecting from the end-wall of the said cup-shaped pole-unit toward the said disk-like pole-unit; a plurality of salient poles projecting from the said disk-like pole-unit toward the end-wall of the said cup-shaped pole-unit; and a ring-like energizing-coil located within the said cup-shaped pole-unit intermediate the flange thereof and the salient poles projecting therefrom; each of the said salient poles of each of the said pole-units being provided with a body-portion of substantially-rectangular form in cross-section and a flux-restricting portion of substantially-circular form in cross-section and of materially-lesser cross-sectional area than the said body-portion. 20 25

14. A stator-structure for synchronous electric-motors, including in combination: a cup-shaped pole-unit having an end-wall and a flange; a disk-like magnetic-portion substantially closing the open end of the said cup-shaped pole-unit; a plurality of salient poles projecting from the end-wall of the said cup-shaped pole-unit toward the said disk-like pole-unit; a plurality of salient poles projecting from the said disk-like pole-unit toward the end-wall of the said cup-shaped pole-unit; and a ring-like energizing-coil located within the said cup-shaped pole-unit intermediate the flange thereof and the salient poles projecting therefrom; each of the said salient poles of each of the said pole-units being provided with a body-portion of substantially-rectangular form in cross-section and a flux-restricting portion of substantially-circular form in cross-section and of materially- 30 35 40 45

lesser cross-sectional area than the said body-portion and located at a point beyond the said body-portion remote from the pole-unit from which the salient pole projects.

15. A stator-structure for synchronous electric-motors, including in combination: a cup-shaped pole-unit having an end-wall and a flange; a disk-like magnetic-portion substantially closing the open end of the said cup-shaped pole-unit; a plurality of salient poles projecting from the end-wall of the said cup-shaped pole-unit toward the said disk-like pole-unit; a plurality of salient poles projecting from the said disk-like pole-unit toward the end-wall of the said cup-shaped pole-unit; and a ring-like energizing-coil located within the said cup-shaped pole-unit intermediate the flange thereof and the salient poles projecting therefrom; each of the said salient poles of each of the said pole-units being provided with a body-portion and having a concaved inner face of relatively-great width and each of the said salient poles also having a flux-restricting portion having a convex inner face. 10 15 20

16. A stator-structure for synchronous electric-motors, including in combination: a cup-shaped pole-unit having an end-wall and a flange; a disk-like magnetic-portion substantially closing the open end of the said cup-shaped pole-unit; a plurality of salient poles projecting from the end-wall of the said cup-shaped pole-unit toward the said disk-like pole-unit; a plurality of salient poles projecting from the said disk-like pole-unit toward the end-wall of the said cup-shaped pole-unit; and a ring-like energizing-coil located within the said cup-shaped pole-unit intermediate the flange thereof and the salient poles projecting therefrom; each of the said salient poles of each of the said pole-units being provided with a body-portion having a concaved inner face of relatively-great width and each of the said salient poles also having a flux-restricting portion having a convex inner face which is located at a point on the salient pole on the side of the said body-portion remote from the pole-unit by which the salient pole is carried. 25 30 35 40 45

ARTHUR B. POOLE.
